(57) **CLAIM**

The ornamental design for a tracking device mounting bracket, as shown and described.

DESCRIPTION

FIG. 1 is a perspective view of a tracking device mounting bracket taken from the top, right, and front, and illustrating a first orientation;

FIG. 2 is another perspective view of the tracking device mounting bracket taken from the bottom, back, and left, and illustrating a second orientation;

FIG. 3 is a front elevation view of the tracking device mounting bracket of FIG. 1;

FIG. 4 back elevation view of the tracking device mounting bracket of FIG. 1;

FIG. 5 is a back elevation view of the tracking device mounting bracket of FIG. 1, and showing a cross-section of the tracking device mounting bracket as cut along the broken line 5 shown in FIG. 8;

FIG. 6 is a right side elevation view of the tracking device mounting bracket of FIG. 1;

FIG. 7 is a left side elevation view of tracking device mounting bracket of FIG. 1;

FIG. 8 is a top plan view of the tracking device mounting bracket of FIG. 1;

FIG. 9 is a top plan view of the tracking device mounting bracket of FIG. 1, and showing a cross-section of the tracking device mounting bracket as cut along the broken line 9 shown in FIG. 4; and,

FIG. 10 is a bottom plan view of the tracking device mounting bracket of FIG. 1.
